FOREIGN PATENT DOCUMENTS

DE 40704326.8 12/2007

Primary Examiner—Caron Veynar*Assistant Examiner*—Katrina A Kile(74) *Attorney, Agent, or Firm*—Cowell & Moring LLP(57) **CLAIM**

The ornamental design for a wheel or wheel cover, as shown and described.

DESCRIPTION

This application contains subject matter similar to the following co-pending U.S. patent application:

Application Ser. No. 29/300,128, filed Feb. 22, 2008.

FIG. 1 is a front view of a wheel or wheel cover according to my novel design; and,

FIG. 2 is a perspective view thereof.

The broken line showing of the rear portion of the wheel rim, central hub, and air valve area is included for the purpose of illustrating environment and form no part of the claimed design.
